(57) **ABSTRACT**

A developing device includes a developer bearer, a first conveying screw conveying developer from one end to another end of a first conveyance path in a first direction, a second conveying screw conveying the developer in a direction opposite to the first direction in a second conveyance path, and a partition having a first communication port communicating the one end of the first conveyance path and the second conveyance path. A shaft diameter of the first conveying screw from one end to a position away from the first communication port by a first predetermined distance is smaller than a shaft diameter of another portion of the first conveying screw. A shaft diameter of the second conveying screw from one end to a position away from the first communication port by a second predetermined distance is larger than a shaft diameter of another portion of the second conveying screw.

APPARATUS**

**CROSS-REFERENCE TO RELATED
APPLICATION**

This patent application is based on and claims priority pursuant to 35 U.S.C. § 119 (a) to Japanese Patent Application No. 2023-097534, filed on Jun. 14, 2023, in the Japan Patent Office, the entire disclosure of which is hereby incorporated by reference herein.

BACKGROUND

Technical Field

Embodiments of the present disclosure relate to a developing device that stores developer such as two-component developer therein, a process cartridge that includes the developing device, and an image forming apparatus.

Related Art

Image forming apparatuses, such as copiers, printers, facsimile machines, and multifunction peripherals (MFPs) including at least two functions of a copier, a printer, and a facsimile machine are known in the art. One type of image forming apparatus includes a developing device. One type of developing device includes a first conveying screw in a first conveyance path, a second conveying screw in a second conveyance path, and a partition between the first conveying screw and the second conveying screw. The first conveying screw conveys developer in the axial direction of the first conveying screw to supply the developer to a developing roller as a developer bearer. The second conveying screw conveys the developer in a direction opposite to a direction in which the first conveying screw conveys the developer.

In such a developing device, the first conveying screw and the second conveying screw form a circulation path for the developer as follows. The first conveying screw conveys the developer from one end of the first conveyance path to the other end of the first conveyance path in the axial direction. The other end of the first conveyance path is not partitioned and has a second communication port, and the developer passes through the second communication port and enters one end of the second conveyance path. In the second conveyance path, the second conveying screw conveys the developer from the one end of the second conveyance path to the other end of the second conveyance path in the axial direction of the second conveying screw. The other end of the second conveyance path is not partitioned and has a first communication port, and the developer passes through the first communication port and enters the one end of the first conveyance path.

SUMMARY

This specification describes an improved developing device that includes a developer bearer, a first conveying screw, a partition, and a second conveying screw. The first conveying screw is disposed in a first conveyance path and faces the developer bearer. The first conveying screw conveys developer from one end of the first conveyance path to another end of the first conveyance path in a first direction along an axial direction of the first conveying screw. The second conveying screw is disposed in a second conveyance

2

path and faces the first conveying screw via the partition. The second conveying screw conveys the developer from one end of the second conveyance path to another end of the second conveyance path in a second direction opposite to the first direction along an axial direction of the second conveying screw. The partition has a first communication port communicating the one end of the first conveyance path and the another end of the second conveyance path and a second communication port communicating the another end of the first conveyance path and the one end of the second conveyance path. The first conveying screw includes a first shaft, a first screw portion wound around the first shaft, a first portion, and a first adjacent portion adjacent to the first portion. The first portion has a first shaft and ranges from one end of the first conveying screw, corresponding to the one end of the first conveyance path, to a position away from the first communication port toward a center of the first conveying screw by a first predetermined distance in the axial direction of the first conveying screw. The first adjacent portion has a second shaft diameter larger than the first shaft diameter. The second conveying screw includes a second shaft, a second screw portion wound around the second shaft, a second portion, and a second adjacent portion adjacent to the second portion. The second portion has a third shaft diameter and ranges from another end of the second conveying screw, corresponding to the another end of the second conveyance path, to a position away from the first communication port toward a center of the second conveying screw by a second predetermined distance in the axial direction of the second conveying screw. The second adjacent portion has a fourth shaft diameter smaller than the third shaft diameter.

This specification also describes an improved developing device that includes a developer bearer, a first conveying screw, a partition, and a second conveying screw. The first conveying screw is disposed in a first conveyance path and faces the developer bearer. The first conveying screw conveys developer from one end of the first conveyance path to another end of the first conveyance path in a first direction along an axial direction of the first conveying screw. The second conveying screw is disposed in a second conveyance path and faces the first conveying screw via the partition. The second conveying screw conveys the developer from one end of the second conveyance path to another end of the second conveyance path in a second direction opposite to the first direction along an axial direction of the second conveying screw. The partition has a first communication port communicating the one end of the first conveyance path and the another end of the second conveyance path and a second communication port communicating the another end of the first conveyance path and the one end of the second conveyance path. The second conveying screw includes a second shaft, a second screw portion wound around the second shaft, a second portion, and a second adjacent portion adjacent to the second portion. The second portion has a large-diameter shaft having a third shaft diameter and ranges from another end of the second conveying screw in the axial direction of the second conveying screw, corresponding to the another end of the second conveyance path, to a position away from the first communication port toward a center of the second conveying screw by a second predetermined distance in the axial direction of the second conveying screw. The second adjacent portion has a reference shaft and a first tapered shaft. The reference shaft has a fourth shaft diameter smaller than the third shaft diameter. The first tapered shaft is between the large-diameter shaft and the reference shaft. The first tapered shaft has a shaft

diameter that gradually decreases from the third shaft diameter to the fourth shaft diameter.

This specification further describes an image forming apparatus including the developing device.

BRIEF DESCRIPTION OF THE DRAWINGS

A more complete appreciation of embodiments of the present disclosure and many of the attendant advantages and features thereof can be readily obtained and understood from the following detailed description with reference to the accompanying drawings, wherein:

FIG. 1 is a schematic diagram illustrating an overall configuration of an image forming apparatus according to an embodiment of the present disclosure;

FIG. 2 is a schematic sectional side view of an image forming device of the image forming apparatus in FIG. 1 to illustrate a configuration of the image forming device;

FIG. 3 is a schematic sectional front view of a developing device;

FIG. 4 is a view of a central portion of a second conveying screw in an axial direction of the second conveying screw;

FIG. 5 is an enlarged view of a part of the second conveying screw illustrated in FIG. 4;

FIG. 6 is an enlarged sectional view of one end of a developing device including a first conveyance path and a second conveyance path in an axial direction of a second conveying screw; and

FIG. 7 is a graph illustrating results of experiments conducted to determine whether or not an abnormal image occurred when the shaft diameter of the large-diameter shaft of the second conveying screw and the shaft diameter of the small-diameter shaft of the first conveying screw were changed.

The accompanying drawings are intended to depict embodiments of the present disclosure and should not be interpreted to limit the scope thereof. The accompanying drawings are not to be considered as drawn to scale unless explicitly noted. Also, identical or similar reference numerals designate identical or similar components throughout the several views.

DETAILED DESCRIPTION

In describing embodiments illustrated in the drawings, specific terminology is employed for the sake of clarity. However, the disclosure of this specification is not intended to be limited to the specific terminology so selected and it is to be understood that each specific element includes all technical equivalents that have a similar function, operate in a similar manner, and achieve a similar result.

As used herein, the singular forms "a," "an," and "the" are intended to include the plural forms as well, unless the context clearly indicates otherwise.

With reference to the drawings, embodiments of the present disclosure are described below. Like reference signs are assigned to identical or equivalent components and a description of those components may be simplified or omitted.

Initially with reference to FIG. 1, a configuration and operation of an image forming apparatus 1 according to an embodiment of the present disclosure is described below.

In FIG. 1, the image forming apparatus 1, which is a tandem color copier in the present embodiment, includes a document conveyance device 3, a scanner 4, an output tray 5, and a sheet feeding device 7. The document conveyance device 3 conveys an original document to the scanner 4. The

scanner 4 reads image data of the original document. An output image is stacked on the output tray 5. The sheet feeding device 7 contains sheets P such as paper sheets.

The image forming apparatus 1 also includes a registration roller pair 9, and four photoconductor drums 11Y, 11M, 11C, and 11BK. The registration roller pair 9 adjusts a conveyance timing of the sheet P. Toner images of yellow, magenta, cyan, and black are formed on the photoconductor drums 11Y, 11M, 11C, and 11BK as image bearers, respectively. The image forming apparatus 1 further includes developing devices 13, primary transfer bias rollers 14, and an intermediate transfer belt 17. The developing devices 13 develop electrostatic latent images formed on the surfaces of the photoconductor drums 11Y, 11M, 11C, and 11BK into toner images of yellow, magenta, cyan, and black, respectively. The primary transfer bias rollers 14 transfer and superimpose the toner images formed on the surfaces of the photoconductor drums 11Y, 11M, 11C, and 11BK onto the intermediate transfer belt 17.

20 The image forming apparatus 1 further includes a secondary-transfer bias roller 18, a fixing device 20, and toner containers 28. The secondary-transfer bias roller 18 transfers the toner images from the intermediate transfer belt 17 onto the sheet P as a color toner image. The fixing device 20 fixes the unfixed color toner image onto the sheet P. The toner containers 28 supply toners of respective colors (yellow, magenta, cyan, and black) to the developing devices 13.

25 The image forming apparatus 1 further includes an operation display panel 100 that displays information relating to printing operations (image forming operations) and allows a user to perform operations relating to the printing operation.

30 A description is given below of typical image forming processes of the image forming apparatus 1 to form the color toner image on the sheet P. The image forming process 35 performed on the surfaces of the photoconductor drums 11Y, 11M, 11C, and 11BK are also described with reference to FIG. 2. A conveyance roller of the document conveyance device 3 conveys the original document from a document table onto a platen (that is, an exposure glass) of the scanner 4. The scanner 4 optically scans the original document on the platen to read image data.

35 Specifically, the scanner 4 irradiates the image of the original document on the platen with light emitted from a light source (e.g., a lamp), thereby scanning the image of the original document. The light reflected from the surface of the original document is imaged on a color sensor via mirrors and lenses. The multicolor image data of the original document is read for each color separation light of red, green, and blue (RGB) by the color sensor and converted into electrical image signals. Further, the image signals are transmitted to an image processor that performs image processing (e.g., color conversion, color calibration, and spatial frequency adjustment) according to the color separation image signals of RGB, and thus image data of yellow, magenta, cyan, and black are obtained.

40 The yellow, magenta, cyan, and black image data are transmitted to the writing device. The writing device emits laser beams L (see FIG. 2) onto the surfaces of the photoconductor drums 11Y, 11M, 11C, and 11BK according to the image data of yellow, magenta, cyan, and black, respectively.

45 Each of the four photoconductor drums 11Y, 11M, 11C, and 11BK rotates clockwise in FIG. 1. Chargers 12 disposed opposite the photoconductor drums 11Y, 11M, 11C, and 11BK uniformly charge the outer circumferential surfaces of the photoconductor drums 11Y, 11M, 11C, and 11BK, respectively, which is referred to as a charging process. As

a result, a charging potential is formed on the surface of each of the photoconductor drums **11Y**, **11M**, **11C**, and **11BK**. Subsequently, the charged surface of each of the photoconductor drums **11Y**, **11M**, **11C**, and **11BK** reaches a position to receive the laser beam **L**.

The writing device emits the laser beam **L** corresponding to four colors from each of four light sources according to the image data. The respective laser beams **L** pass through different optical paths for components of yellow, magenta, cyan, and black. The above process is an exposure process.

For example, the surface of the leftmost photoconductor drum **11Y** in FIG. 1 is irradiated with a laser beam corresponding to the image data of yellow. A polygon mirror that rotates at high velocity deflects the laser beam for yellow along the axis of rotation of the photoconductor drum **11Y** (i.e., a main scanning direction) so that the laser beam scans the surface of the photoconductor drum **11Y**. Thus, an electrostatic latent image corresponding to the yellow image data is formed on the photoconductor drum **11Y** charged by the charger **12**.

Similarly, the writing device irradiates the outer circumferential surface of the second photoconductor drum **11M** from the left in FIG. 1 with the laser beam corresponding to the magenta component to form an electrostatic latent image corresponding to the magenta component. The writing device irradiates the outer circumferential surface of the third photoconductor drum **11C** from the left in FIG. 1 with the laser beam corresponding to the cyan component to form an electrostatic latent image corresponding to the cyan component. The writing device irradiates the outer circumferential surface of the fourth photoconductor drum **11BK** from the left in FIG. 1 with the laser beam corresponding to the black component to form an electrostatic latent image corresponding to the black component.

Subsequently, the surface of each of the photoconductor drums **11Y**, **11M**, **11C**, and **11BK** bearing the electrostatic latent images reaches a developing position opposite each developing device **13**. The developing devices **13** supply corresponding color toners to the photoconductor drums **11Y**, **11M**, **11C**, and **11BK** to develop the latent images on the photoconductor drums **11Y**, **11M**, **11C**, and **11BK** into single-color toner images, respectively. This is a development process.

After the development process, the surfaces of the photoconductor drums **11Y**, **11M**, **11C**, and **11BK** reach positions facing the intermediate transfer belt **17**. The primary transfer bias rollers **14** are disposed at the positions at which the photoconductor drums **11Y**, **11M**, **11C**, and **11BK** face the intermediate transfer belt **17** and in contact with an inner surface of the intermediate transfer belt **17**, respectively.

At the positions of the primary transfer bias rollers **14**, the toner images on the photoconductor drums **11Y**, **11M**, **11C**, and **11BK** are sequentially transferred to and superimposed on the intermediate transfer belt **17**, forming a multicolor toner image thereon, which is referred to as a primary transfer process.

After the primary transfer process, the surfaces of the photoconductor drums **11Y**, **11M**, **11C**, and **11BK** reach positions opposite cleaning devices **15**, respectively. The cleaning device **15** removes and collects the residual (untransferred) toner from the outer circumferential surface of each of the photoconductor drums **11Y**, **11M**, **11C**, and **11BK**, which is referred to as a cleaning process.

After the cleaning process, the outer circumferential surfaces of the photoconductor drums **11Y**, **11M**, **11C**, and

11BK pass by dischargers to complete a series of image forming processes performed on the photoconductor drums **11Y**, **11M**, **11C**, and **11BK**.

As described above, the multicolor toner image is formed on the intermediate transfer belt **17** by transferring and superimposing the respective single-color toner images formed on the photoconductor drums **11Y**, **11M**, **11C**, and **11BK**. Then, the intermediate transfer belt **17** bearing the multicolor toner image moves counterclockwise in FIG. 1 to reach a position opposite the secondary-transfer bias roller **18** (i.e., a secondary transfer nip). At the secondary transfer nip, the secondary-transfer bias roller **18** transfers the multicolor toner image from the intermediate transfer belt **17** onto the sheet **P**, which is referred to as a secondary transfer process.

After the secondary transfer process, the surface of the intermediate transfer belt **17** reaches the position opposite an intermediate-transfer-belt cleaner. The intermediate-transfer-belt cleaner collects untransferred toner adhering to the intermediate transfer belt **17** to complete a series of transfer processes performed on the intermediate transfer belt **17**.

The sheet **P** is conveyed from the sheet feeding device **7** via a registration roller pair **9** to the secondary transfer nip between the intermediate transfer belt **17** and the secondary-transfer bias roller **18**.

Specifically, a feed roller **8** feeds the sheet **P** from the sheet feeding device **7** that stores a stack of sheets **P**, and the sheet **P** is then guided by the sheet conveyance guide to the registration roller pair **9**. The sheet **P** that has reached the registration roller pair **9** is conveyed toward the secondary transfer nip, timed to coincide with the arrival of the multicolor toner image on the intermediate transfer belt **17**.

After the multicolor toner image is transferred onto the sheet **P**, the sheet **P** is conveyed to the fixing device **20**. The fixing device **20** includes a fixing roller and a pressure roller pressing against each other. In a nip between the fixing roller and the pressure roller, the multicolor toner image is fixed on the sheet **P**. After the fixing process, an output roller pair ejects the sheet **P** as the output image to the exterior of the image forming apparatus **1**, and the ejected sheet **P** is stacked on the output tray **5** to complete the series of image forming processes.

Image forming devices in the image forming apparatus illustrated in FIG. 1 are described in detail below with reference to FIGS. 2 and 3.

FIG. 2 is a schematic sectional side view of the image forming device viewed in a cross-section orthogonal to the rotation axis of the photoconductor drum **11** to illustrate the configuration of the image forming device. FIG. 3 is a schematic sectional front view of the developing device **13** as viewed in a cross-section parallel to the rotation axis direction of the photoconductor drum **11** and the vertical direction to illustrate parts extending in the longitudinal direction of the developing device **13**.

Since the image forming devices have substantially the same structure, the image forming device and the developing device illustrated in FIGS. 2 and 3 omit the alphabet **Y**, **C**, **M**, and **BK** from the reference numerals.

As illustrated in FIG. 2, the image forming device includes, for example, the photoconductor drum **11** as the image bearer, the charger **12**, the developing device **13**, and the cleaning device **15**.

The photoconductor drum **11** as the image bearer is a negatively-charged organic photoconductor and is driven to rotate clockwise in FIG. 2 by a rotary drive source.

The charger **12** is an elastic charging roller and includes a core and an elastic layer of moderate resistivity, covering

the core. For example, the elastic layer is a foamed urethane layer that includes urethane resin, carbon black, as conductive particles, a sulfuration agent, and a foaming agent. The material of the medium resistance layer of the charger 12 is, for example, a rubber material in which a conductive substance such as carbon black or a metal oxide for resistance adjustment is dispersed in urethane, ethylene-propylene-diene polyethylene (EPDM), butadiene acrylonitrile rubber (NBR), silicone rubber, or isoprene rubber, or a foamed material thereof.

The cleaning device 15 includes a cleaning blade that is in sliding contact with the photoconductor drum 11. The cleaning device 15 mechanically removes and collects the untransferred toner on the photoconductor drum 11.

The developing device 13 includes a developing case 13j having an opening A and a developing roller 13a serving as a developer bearer facing the photoconductor drum 11 with a minute gap between the developing roller 13a and the photoconductor drum 11 via the opening A. The developing device 13 accommodates developer G (two component developer) including toner T and carrier C. The developer G rises up on the developing roller 13a to form a magnetic brush in a facing portion in which the developing roller 13a and the photoconductor drum 11 face each other. The magnetic brush contacts the photoconductor drum 11 in the facing region to form a development region. The developing device 13 develops the electrostatic latent image formed on the surface of the photoconductor drum 11 to form a toner image. The configuration and operation of the developing device 13 are described in detail below.

Referring to FIG. 1, the toner container 28 contains the toner T to be supplied to the developing device 13. Specifically, a magnetic sensor is attached to the developing device 13 to detect toner concentration that is a proportion of the toner in the developer G. Based on data of the toner concentration, the toner T is appropriately supplied from the toner container 28 to a supply port 13d (see FIG. 3) of the developing device 13 through a toner transport pipe.

The developing device 13 in the image forming apparatus is described in detail below.

As illustrated in FIGS. 2 and 3, the developing device 13 includes a developing roller 13a as a developer bearer, a first conveying screw 13b1 as a first conveyor, a second conveying screw 13b2 as a second conveyor, a round-bar doctor 13c as a developer regulator, a partition 13e as a wall, and a filter 13k covering an exhaust port 13j1 of the developing case 13j. These members 13a, 13b1, 13b2, 13c, 13e, 13k are in the developing case 13j that is a housing.

The developing roller 13a as the developer bearer includes a sleeve 13a2 that is a cylinder made of nonmagnetic material such as aluminum, brass, stainless steel, or conductive resins. A driver such as a driving motor 91 rotates the sleeve 13a2 in the direction indicated by an arrow illustrated in FIG. 2 together with the first conveying screw 13b1 and the second conveying screw 13b2.

Inside the sleeve 13a2 of the developing roller 13a, a magnet 13a1 is fixed, and the magnet 13a1 forms a plurality of magnetic poles that are an S1 pole, an N1 pole, an S2 pole, an N2 pole, and an N3 pole on the peripheral surface of the sleeve 13a2.

The sleeve 13a2 of the developing roller 13a rotates in a predetermined direction (that is counterclockwise direction in FIG. 2) to convey the developer G borne on the developing roller 13a, and the developer G reaches the position of the round-bar doctor 13c as the developer regulator. The round-bar doctor 13c adjusts the amount of the developer G on the developing roller 13a to a proper amount at the

position. Subsequently, the rotation of the sleeve 13a2 of the developing roller 13a conveys the developer to the developing area in which the developing roller 13a faces the photoconductor drum 11. An electric field (a developing electric field) formed in the developing area deposits toner on the electrostatic latent image formed on the photoconductor drum 11.

Referring to FIG. 2, the magnet 13a1 forms the plurality of magnetic poles around the sleeve 13a2 of the developing roller 13a. The magnetic poles include the N1 pole as a main magnetic pole, the S2 pole as a transport magnetic pole, the N2 pole as a pre-developer-release magnetic pole, a developer-release magnetic pole that is the north pole, the N3 pole as a post-developer-release magnetic pole, and the S1 pole as a scooping magnetic pole. The N1 pole is formed at a position facing the photoconductor drum 11. The S2 pole is formed at a position downstream from the N1 pole in the rotation direction of the developing roller 13a and the position facing an upper part of the developing case 13j. the N2 pole is formed at a position downstream from the S2 pole in the rotation direction in an obliquely upper part of the developing roller 13a. The developer-release magnetic pole is formed at a position between the N2 pole and the N3 pole and the position above the first conveyance path B1. The N3 pole is formed at a position downstream from the developer-release magnetic pole and the position above the first conveyance path B1. The S1 pole is formed from a position facing the first conveying screw 13b1 to a position close to a position facing the round-bar doctor 13c.

Specifically, the S1 pole as the scooping magnetic pole acts on the carrier as magnetic materials to scoop up the developer G contained in the first conveyance path B1 onto the developing roller 13a. A part of the developer G borne on the developing roller 13a is scraped off at the position of the round-bar doctor 13c as the developer regulator and returned to the first conveyance path B1. Another part of the developer G borne on the developing roller 13a passes through a doctor gap between the round-bar doctor 13c and the developing roller 13a at the position of the round-bar doctor 13c in which the magnetic force of the S1 pole acts and stands at the position of the N1 pole as the main magnetic pole to form the magnetic brush in the development region and slidably contacts the photoconductor drum 11. Thus, the toner T in the developer G borne on the developing roller 13a adheres to the latent image formed on the photoconductor drum 11. After the developer G passes through the position of the N1 pole, the S2 pole and the N2 pole convey the developer G to the position of the developer-release magnetic pole that is the north pole. At the position of the developer-release magnetic pole, a repulsive magnetic field is formed on the developing roller 13a. The repulsive magnetic field acts on the carrier to separate the developer G from the developing roller 13a. As a result, the developer G borne on the developing roller 13a after the developing process is separated from the developing roller 13a. The developer G separated from the developing roller 13a falls into the first conveyance path B1, and the first conveying screw 13b1 collects the developer G and conveys the developer G toward a downstream portion of the first conveyance path B1.

Five poles that are the S1 pole, the N1 pole, the S2 pole, the N2 pole, and the N3 pole are magnetized on the magnet 13a1 of the developing roller 13a but form the above-described six magnetic poles. Of the six magnetic poles, the developer-release magnetic pole (the north pole) is not directly formed by a pole magnetized on the magnet 13a1. The developer-release magnetic pole is formed between two

magnetic poles (the N2 pole and the N3 pole) having the same polarity (the north pole in this embodiment).

The five poles described above may be formed in such a manner that the S pole and the N pole are reversed.

With reference to FIG. 2, the round-bar doctor 13c as the developer regulator has a cylindrical shape, is made of magnetic material, and is below the developing roller 13a. The developing roller 13a rotates counterclockwise in FIG. 2, and the photoconductor drum 11 rotates clockwise in FIG. 2.

With such a configuration, the photoconductor drum 11 is disposed below the intermediate transfer belt 17 to shorten the conveyance path of the sheet P and to reduce the size of the body of the image forming apparatus 1 in the horizontal direction. The rotation direction of the developing roller 13a with respect to the photoconductor drum 11 in a developing gap is the forward direction. Setting the rotation direction of the developing roller 13a to the forward direction can sufficiently obtain the developing time in the developing gap and enhance the developing performance, as compared with the developing device in which the round-bar doctor 13c is disposed above the developing roller 13a and the rotation direction of the developing roller 13a with respect to the photoconductor drum 11 is set to the reverse direction.

As illustrated in FIG. 3, the two conveyors that are the first conveying screw 13b1 and the second conveying screw 13b2 stir and mix the developer G accommodated in the developing device 13 while circulating the developer G in the developing device 13. Each of the first conveying screw 13b1 and the second conveying screw 13b2 conveys the developer in the axial direction of each of the first conveying screw 13b1 and the second conveying screw 13b2, which is the left-right direction in FIG. 3 and the direction perpendicular to the surface of the paper on which FIG. 2 is drawn.

The first conveying screw 13b1 is disposed below the developing roller 13a and faces the developing roller 13a. The first conveying screw 13b1 horizontally conveys the developer G in the axial direction. In other words, the first conveying screw 13b1 conveys the developer G in a first direction along the axial direction of the first conveying screw 13b1 that is from right to left as indicated by a broken line arrow in FIG. 3. The first conveying screw 13b1 supplies developer G onto the developing roller 13a at the position of the scooping magnetic pole (the S1 pole). In addition, the first conveying screw 13b1 conveys the developer G that is separated from the developing roller 13a at the position of the developer-release magnetic pole (the north pole) and falls into the first conveyance path B1 in a direction from one end of the first conveying screw 13b1 to the other end of the first conveying screw 13b1 in the first direction, in other words, toward the downstream portion of the first conveying screw 13b1 in a conveyance direction of the developer G. The first conveying screw 13b1 rotates clockwise in FIG. 2.

The second conveying screw 13b2 is disposed below the first conveying screw 13b1 and at a position facing the developing roller 13a via the first conveying screw 13b1. The second conveying screw 13b2 horizontally conveys the developer G in the second conveyance path B2 in the longitudinal direction. In other words, the second conveying screw 13b2 conveys the developer G in a second direction opposite to the first direction, and the second direction is along the axial direction of the second conveying screw and is from left to right as indicated by the broken line arrow in FIG. 3. In the present embodiment, the second conveying screw 13b2 is designed to rotate forward, in other words,

counterclockwise in FIG. 2 that is opposite to the rotation direction of the first conveying screw 13b1.

The sleeve 13a2 of the developing roller 13a, the first conveying screw 13b1, and the second conveying screw 13b2 each have a shaft and a gear fixed at one end of the shaft that is the right end of the shaft in FIG. 3, and these gears form a gear train. The driving force of the driving motor 91 is transmitted to the gear train to rotate the developing roller 13a, the first conveying screw 13b1, and the second conveying screw 13b2 in the above-described rotation directions.

The first conveying screw 13b1 conveys the developer G in the first conveyance path B1 in the axial direction of the first conveying screw 13b1 (in other words, the first direction). The partition 13e is not in the upstream portion of the first conveyance path B1 in a developer conveyance direction in which the developer G is conveyed in the first conveyance path B1 to form a first communication port 13f (in other words, a first relay portion). The partition 13e is not also in the downstream portion of the first conveyance path B1 in the developer conveyance direction to form a second communication port 13g (in other words, a second relay portion). As indicated by the broken line arrow in FIG. 3, the developer G is conveyed by the first conveying screw 13b1, passes through the second communication port 13g, is conveyed by the second conveying screw 13b2, passes through the first communication port 13f, and is conveyed again by the first conveying screw 13b1. Thus, the developer G circulates in the developing device.

Similar to the developing roller 13a and the photoconductor drum 11, the first conveying screw 13b1 and the second conveying screw 13b2 are disposed in a manner such that the rotation axes of the first conveying screw 13b1 and the second conveying screw 13b2 are substantially horizontal. Each of the first conveying screw 13b1 and the second conveying screw 13b2 has a screw portion spirally wound around a shaft of each of the first conveying screw 13b1 and the second conveying screw 13b2, and the screw portion has a predetermined screw pitch and a predetermined number of threads. The screw portion may have one thread or multiple threads.

The first conveyance path B1 including the first conveying screw 13b1 and the second conveyance path B2 including the second conveying screw 13b2 are separated from each other by the partition 13e as the wall except for both ends of the first conveyance path B1 and the second conveyance path B2 in the axial direction of the first conveying screw 13b1.

With reference to FIG. 3, in the developer conveyance direction, an upstream end of the first conveyance path B1 including the first conveying screw 13b1 communicates with a downstream end of the second conveyance path B2 including the second conveying screw 13b2 via the first communication port 13f. In other words, the first communication port 13f is formed at one end of the developing device 13 in the axial direction so that the developer conveyed downstream by the second conveying screw 13b2 as the second conveyor flows into the upstream end of the first conveyance path B1 in the developer conveyance direction, and the first conveying screw 13b1 as the first conveyor conveys the developer from the upstream end to a downstream end of the first conveyance path B1 (in other words, the first conveyor conveys the developer in the first direction). The developer G conveyed by the second conveying screw 13b2 reaches the downstream end of the second conveyance path B2, stays and rises in the vicinity of the first communication port 13f, passes through the first

11

communication port **13f**, and is conveyed (delivered) to the upstream end of the first conveyance path **B1**, and the first conveying screw **13b1** conveys the developer **G**.

With reference to FIG. 3, in the developer conveyance direction, the downstream end of the first conveyance path **B1** including the first conveying screw **13b1** communicates with an upstream end of the second conveyance path **B2** including the second conveying screw **13b2** via the second communication port **13g**. In other words, the second communication port **13g** is formed at the other end of the developing device **13** in the axial direction so that the developer conveyed downstream by the first conveying screw **13b1** as the first conveyor flows into the upstream end of the second conveyance path **B2** in the developer conveyance direction, and the second conveying screw **13b2** as the second conveyor conveys the developer from the upstream end to the downstream end of the second conveyance path **B2** (in other words, the second conveyor conveys the developer in the second direction opposite to the first direction). In the first conveyance path **B1**, the first conveying screw **13b1** conveys the developer **G** that is not supplied to the developing roller **13a**. In addition, the first conveying screw **13b1** conveys the developer **G** that is separated from the developing roller **13a** at the position of the developer-release magnetic pole (north pole) and falls into the first conveyance path **B1**. The developer **G** reaches the second communication port **13g** at the downstream end of the first conveyance path **B1** in the developer conveyance direction and falls into the upstream end of the second conveyance path **B2** in the developer conveyance direction by its own weight.

In the above-described configuration, the two conveyors (i.e., the first conveying screw **13b1** and the second conveying screw **13b2**) form a circulation pathway in which the developer **G** is conveyed in the axial direction of the first conveying screw **13b1** and the axial direction of the second conveying screw **13b2** (in other words, in the longitudinal direction of the developing device **13**) and circulates in the developing device **13**. In other words, while a controller **90** controls the driving motor **91** to drive the developing device **13**, the developer **G** accommodated in the developing device **13** flows in the direction indicated by the broken line arrow in FIG. 3.

Not horizontally but vertically forming the circulation pathway of the developer **G** (the first conveyance path **B1** and the second conveyance path **B2**) under the developing roller **B2** as described above can reduce the horizontal size of the developing device **13** (in other words, can extend the vertical size of the developing device **13**). In particular, in the tandem color image forming apparatus **1** in which the multiple developing devices **13** (image forming devices) are arranged in parallel in the horizontal direction, reducing the horizontal sizes of the multiple developing devices **13** (image forming devices) can effectively reduce the entire horizontal size of the image forming apparatus **1**.

A magnetic sensor is disposed under the second conveying screw **13b2** in the second conveyance path **B2** to detect the toner concentration of the developer **G** circulating in the developing device **13**. Based on the data of the toner concentration detected by the magnetic sensor, the controller **90** controls a toner supply system to supply new toner **T** from the toner container **28** (see FIG. 1) to the supply port **13d** that is in the left end of the developing device **13** in FIG. 3. The supply port **13d** is closer to the second communication port **13g** formed at the other end of the developing device **13** in the axial direction than to the first communication port **13f**.

12

Referring to FIG. 3, the supply port **13d** (in other words, a toner supply inlet) is disposed above the upstream end of the second conveyance path **B2** formed by the second conveying screw **13b2** and away from the development region (outside the range of the developing roller **13a** in the axial direction of the developing roller **13a**).

In other words, the second conveyance path **B2** includes an extending portion **B2a** extending outside from the second communication port **13g** formed at the other end of the developing device **13** in the axial direction (that is the left end of the developing device **13** in FIG. 3) to supply the toner **T** for the development process.

The new toner **T** is discharged from the toner container **28**, appropriately supplied to the supply port **13d** (supplied in the direction indicated by the white arrow in FIG. 3), and conveyed to the inside of the developing device **13**. Disposing the supply port **13d** in the vicinity of the second communication port **13g** as described above enables the supplied toner to be sufficiently dispersed and mixed with the developer **G** fell by its own weight and supplied to the downstream end of the second conveyance path **B2** from the second communication port **13g** over a relatively long time.

The toner **T** used in the present embodiment (the toner in the developer **G**, the toner in the toner container **28**) may be polymerization toner having a small diameter of about 5.0 to 6.0 μm in volume average particle diameter.

A small-diameter carrier formed to have a weight average particle diameter of 20 to 60 μm may be used as carrier **C** in the developer **G**.

The configuration and operation of the developing device **13** according to the present embodiment is described below.

As described above with reference to FIGS. 2 and 3, the developing device **13** according to the present embodiment includes the developing roller **13a** as a developer bearer, the first conveying screw **13b1**, and the second conveying screw **13b2**. The developing device **13** in the present embodiment includes a relatively small amount of developer **G** inside the developing device **13**, in other words, employs a small amount of developer system.

The developing roller **13a** as the developer bearer develops the latent images formed on the surfaces of the photoconductor drum **11** as the image bearer. In the present embodiment, the developing roller **13a** has an outer diameter of about 16 mm.

The first conveying screw **13b1** is disposed in the first conveyance path **B1** to face the developing roller **13a** as the developer bearer. While the first conveying screw **13b1** rotates in a predetermined direction indicated by the arrows in FIGS. 2 and 3 during the development process to convey the developer **G** from one end of the first conveyance path **B1** in the first direction along the axial direction of the first conveying screw **13b1** (that is the right end of the first conveyance path **B1** in FIGS. 3 and 6) to the other end of the first conveyance path **B1** in the first direction (that is the left end of the first conveyance path **B1** in FIG. 3), the magnetic force of the scooping magnetic pole attracts the developer **G** to the developing roller **13a**, and the developer **G** is borne on the developing roller **13a**. Thus, the first conveying screw **13b1** supplies the developer **G** to the developing roller **13a**.

The first conveying screw **13b1** includes a first shaft **13b11** and a first screw portion **13b12**. The first shaft **13b11** extends in the axial direction of the first conveying screw **13b1** that is the lateral direction in FIGS. 3 and 6 and a direction perpendicular to the surface of the paper on which FIG. 2 is drawn. The first screw portion **13b12** is spirally wound around the first shaft **13b11**. In the present embodiment, the first conveying screw **13b1** has a total length of

13

about 272 mm in the axial direction, and the first screw portion **13b12** has an outer diameter of about 12 mm, a lead length of about 45 mm, a number of threads of three. A rotational speed of the first conveying screw is about 275 rpm.

The first shaft **13b11** of the first conveying screw **13b1** includes a reference shaft **13b11a** having a shaft diameter **M1** as a first shaft diameter that is about 8 mm, a small-diameter shaft **13b11b** having a second shaft diameter smaller than the first shaft diameter, and a tapered shaft **13b11c**, which is described in detail below with reference to FIG. 6.

The second conveying screw **13b2** is disposed in the second conveyance path **B2** so as to face the first conveying screw **13b1** as the first conveyor via the partition **13e**. While the second conveying screw **13b2** rotates in a predetermined direction indicated by the arrows in FIGS. 2 and 3 during the development process to convey the developer **G** from one end of the second conveyance path **B2** in the second direction opposite to the first direction (that is the left end of the second conveyance path **B2** in FIG. 3) to the other end of the second conveyance path in the second direction (that is the right end of the second conveyance path **B2** in FIGS. 3 and 6), the second conveying screw **13b2** stirs the developer **G**.

The second conveying screw **13b2** includes a second shaft **13b21** and a second screw portion **13b22**. The second shaft **13b21** extends in the axial direction that is the lateral direction in FIGS. 3 and 6 and the direction perpendicular to the surface of the paper on which FIG. 2 is drawn. The second screw portion **13b22** is spirally wound around the second shaft **13b21**. In the present embodiment, the second conveying screw **13b2** has a total length of about 304 mm in the axial direction, and the second screw portion **13b22** has an outer diameter of about 12.5 mm, a lead length of about 20 mm, a number of threads of two (but a part of the second screw portion has one thread). A rotational speed of the second conveying screw is about 319 rpm.

In the present embodiment, the second conveyance path **B2** is disposed below the first conveyance path **B1** as illustrated in FIG. 2.

The second shaft **13b21** of the second conveying screw **13b2** includes a reference shaft **13b21a** having a shaft diameter **N1** that is about 5 mm, a large-diameter shaft **13b21b**, a first tapered shaft **13b21c**, and a second tapered shaft **13b21d**, which is described in detail below with reference to FIG. 6.

As described above with reference to FIG. 3, the developing device **13** according to the present embodiment has the first communication port **13f** as a first opening and the second communication port **13g** as a second opening to form the circulation pathway including the first conveyance path **B1** and the second conveyance path **B2**.

The first communication port **13f** is an opening of the partition **13e** that communicates the one end of the first conveyance path **B1** in the first direction and the other end of the second conveyance path **B2** in the second direction opposite to the first direction (in the right end of the developing device in FIGS. 3 and 6). The first communication port **13f** in the present embodiment is opened in a range of 5 to 12 mm from the inner surface of a wall of the developing device **13** that forms one edge of the first conveyance path **B1** in the axial direction toward the center of the first conveyance path **B1** in the axial direction.

In contrast, the second communication port **13g** is another opening of the partition **13e** that communicates the other end of the first conveyance path **B1** in the first direction and the

14

one end of the second conveyance path **B2** in the second direction opposite to the first direction (in the left end of the developing device in FIG. 3). The second communication port **13g** in the present embodiment is opened in a range of 5 to 1.5 to 7 mm from the inner surface of a wall of the developing device **13** that forms the other edge of the first conveyance path **B1** in the axial direction toward the center of the first conveyance path **B1** in the axial direction. Designing the opening of the first communication port **13f** to be larger than the opening of the second communication port **13g** enables flowing a larger amount of developer **G** in the first conveyance path **B1** than that in the second conveyance path **B2**.

With reference to FIGS. 3 to 5, the second conveying screw **13b2** in the present embodiment is described below in more detail.

Referring to FIG. 3, the second screw portion **13b22** and the second shaft **13b21** of the second conveying screw **13b2** in the present embodiment have different shapes in three regions **X1** to **X3** and the extending portion **B2a**.

The extending portion **B2a** is the most upstream portion of the developing device **13** in the developer conveyance direction of the developer conveyed by the second conveying screw **13b2** and guides the new toner **T** supplied from the supply port **13d** to the circulation pathway. The second conveying screw **13b2** in the extending portion **B2a** has a length of about 41 mm in the axial direction. The second screw portion in the extending portion **B2a** has an outer diameter of about 8.4 mm, a lead length of about 12 mm, and one thread. A shaft diameter of the second shaft **13b21** in the extending portion **B2a** is about 5 mm.

A third region **X3** is next to the extending portion **B2a**. The second conveying screw **13b2** in the third region **X3** has a length of about 60 mm in the axial direction. The second screw portion **13b22** in the third region **X3** has an outer diameter of about 12.5 mm, a lead length of about 20 mm, and the number of threads is two. The shaft diameter **N1** of the second shaft **13b21** in the third region **X3** is about 5 mm.

A second region **X2** is next to the third region **X3**. Referring to FIGS. 4 and 5, the second region **X2** has regions **X21** and regions **X22**. In the regions **X21** and **X22**, a part of the second screw portion **13b22** (the part **W** surrounded by broken lines in FIG. 4) is removed. In addition, two projections **13b23** are disposed on the second shaft **13b21** in the region **X21**. The projection **13b23** is a plate having a thickness of about 1.5 mm and a horizontal and vertical size of 3.5 mm×5 mm and inclined by 30° in the forward direction with respect to the rotation axis of the second conveying screw **13b2**. The region **X2** has two pairs of the region **X21** and the region **X22** arranged in series. The second screw portion **13b22** in the second region **X2** has an outer diameter of about 12.5 mm, a lead length of about 20 mm, and the number of threads is two. The shaft diameter **N1** of the second shaft **13b21** in the second region **X2** is about 5 mm.

A first region **X1** is next to the second region **X2**. A part of the second conveying screw **13b2** in the first region **X1** is referred to as a second portion, and a part of the second conveying screw **13b2** in the second region **X2** is referred to as a second adjacent portion.

The second portion includes the large-diameter shaft **13b21b** and the second tapered shaft **13b21d**, and the second adjacent portion includes the first tapered shaft **13b21c**, which is described in detail below with reference to FIG. 6.

Referring to FIGS. 4 and 5, the second conveying screw **13b2** in the second region **X2** has cutout portions **W** formed

by cutting out the second screw portion **13b22** at 90° with respect to a rotation axis direction of the second conveying screw **13b2**.

Since the developing device **13** in the present embodiment adopts the small amount of developer system for cost reduction as described above, the amount of the developer conveyed in the second conveyance path **B2** (in other words, a conveyance performance) is adjusted to an appropriate amount so that the amount of the developer in the first conveyance path **B1** does not become insufficient. In the present embodiment, since the second conveying screw **13b2** in the second region **X2** has the cutout portions **W** that reduce the conveyance performance of the developer **G**, the developer **G** is pooled in a space formed by each of the cutout portions **W**.

As illustrated in FIG. 5, the developer **G** pooled in the space formed by the cutout portion **W** is conveyed in a direction indicated by an arrow **E** and collides with the projection **13b23**. The developer that has collided is divided into two directions that are a direction indicated by an arrow **E1** and a direction indicated by an arrow **E2**. The developer conveyed in the direction indicated by the arrow **E1** is mixed with the developer conveyed in a direction indicated by an arrow **D**. On the other hand, the developer **G** pooled in the space formed by the other cutout portion **W** is conveyed in a direction indicated by an arrow **F**, collides with the projection **13b23**, and is divided into two directions that are a direction indicated by an arrow **F1** and a direction indicated by an arrow **F2**. The developer conveyed in the direction indicated by the arrow **F1** is mixed with the developer conveyed in a direction indicated by an arrow **E1**. As described above, the developer is mixed in the second region **X2**. As a result, in the second region **X2**, the toner is mixed and dispersed in the developer **G**, and the conveyance performance of the developer **G** is adjusted and optimized.

As illustrated in FIG. 6, the first conveying screw **13b1** has a first region **Z1** and a second region **Z2**. The first region **Z1** extends from one end of the first conveying screw **13b1** in the axial direction of the first conveying screw **13b1** (that is the left end of the first conveying screw **13b1** in FIG. 6) to a position away from the first communication port **13f** toward the center of the first conveying screw **13b1** in the axial direction by a first predetermined distance **H1** (that is about 12.5 mm). The first region **Z1** is referred to as a first portion of the first conveying screw **13b1**. The second region **Z2** is a region of the first conveying screw **13b1** other than the first region **Z1** and is referred to as a first adjacent portion adjacent to the first portion. The first shaft **13b11** has the shaft diameter **M1** in the second region **Z2** (in other words, the first adjacent portion) and the shaft diameter **M2** in the first region **Z1** (in other words, the first portion) smaller than the shaft diameter **M1**, and the first screw portion **13b12** is wound around the first shaft **13b11**. In other words, the first shaft **13b11** has the first portion having a first shaft diameter **M2** and the first adjacent portion having a second shaft diameter **M1** larger than the first shaft diameter **M2**.

The first shaft **13b11** of the first conveying screw **13b1** includes the reference shaft **13b11a**, the small-diameter shaft **13b11b**, and the tapered shaft **13b11c**.

The small-diameter shaft **13b11b** is in the first region **Z1** having a length in the axial direction that is substantially the same as a length of the above-described first region **X1** of the second conveying screw **13b2** in the axial direction. The small-diameter shaft **13b11b** has the shaft diameter **M2** as the first shaft diameter of about 6.5 mm, a length of about

28.5 mm in the axial direction, and a screw height (that is the height from the shaft to the tip of the screw projecting from the shaft) of about 2.75 mm.

The reference shaft **13b11a** is in a part of the second region **Z2** that is the region of the first conveying screw **13b1** other than the first region **Z1** as the first portion and has the shaft diameter **M2** larger than the shaft diameter **M1** of the small-diameter shaft **13b11b**. In other words, the reference shaft **13b11a** is in the first adjacent portion of the first conveying screw **13b1** and has the second shaft diameter **M1** larger than the first shaft diameter **M2**.

The tapered shaft **13b11c** is in a region **Z1a** between the small-diameter shaft **13b11b** and the reference shaft **13b11a** and not in the first region **Z1** as the first portion. The diameter of the tapered shaft **13b11c** gradually increases from the shaft diameter **M2** equivalent to the diameter of the small-diameter shaft **13b11b** to the shaft diameter **M1** equivalent to the diameter of the reference shaft **13b11a**.

As illustrated in FIG. 6, the second conveying screw **13b2** has the first region **X1** and the second region **X2**. The first region **X1** extends from one end of the second conveying screw **13b2** (that is the left end of the second conveying screw **13b2** in FIG. 6) to a position away from the first communication port **13f** toward the center of the second conveying screw **13b2** in the axial direction by a second predetermined distance **H2** (that is about 12.5 mm and substantially the same as the first predetermined distance **H1**). The first region **X1** is referred to as the second portion of the second conveying screw **13b2**, and the second region **X2** is referred to as a second adjacent portion. The second shaft **13b21** has the shaft diameter **N1** in the second region **X2** (in other words, the second adjacent portion) and the shaft diameter **N2** in the first region **X1** (in other words, the second portion) larger than the shaft diameter **N1**, and the second screw portion **13b22** is wound around the second shaft **13b21**.

In other words, the second conveying screw conveys the developer from one end of the second conveyance path to the other end of the second conveyance path in the second direction opposite to the first direction along the axial direction of the second conveying screw. The second conveying screw has the second portion from the other end of the second conveying screw, corresponding to the other end of the second conveyance path, in the second direction to a position away from the first communication port toward the center of the second conveying screw by the second predetermined distance in the axial direction of the second conveying screw. The second shaft has the second portion **X1** having a third shaft diameter **N2** and the second adjacent portion having a fourth shaft diameter **N1** smaller than the third shaft diameter **N2**.

The second shaft **13b21** of the second conveying screw **13b2** includes the reference shaft **13b21a**, the large-diameter shaft **13b21b**, and the first tapered shaft **13b21c** as a first tapered shaft.

The large-diameter shaft **13b21b** is in the first region **X1** as the second portion. The large-diameter shaft **13b21b** has a shaft diameter **N2** as the third shaft diameter of about 7 mm, a length of about 28.5 mm including a length of about 1.5 mm of a second tapered shaft **13b21d** in the axial direction, and a screw height of about 2.75 mm.

A winding direction of the second screw portion **13b22** at the downstream end of the large-diameter shaft **13b21b** (including the second tapered shaft **13b21d**) is opposite to a winding direction of the second screw portion **13b22** at the portion other than the downstream end. The above-described

structure prevents the developer G from staying at the one end of the second conveyance path B2 in the axial direction of the second conveying screw 13b2, increasing the developer pressure, agglomerating, or leaking out of the developing device.

The reference shaft 13b21a is in a part of the second region X2 that is the region of the second conveying screw 13b2 other than the first region X1 as the second portion and has the shaft diameter N1 smaller than the shaft diameter N2 of the large-diameter shaft 13b21b. In other words, the reference shaft 13b21a is in the second adjacent portion and has the fourth shaft diameter N1 smaller than the third shaft diameter N2.

The first tapered shaft 13b21c is in a region X1a between the large-diameter shaft 13b21b and the reference shaft 13b21a and not in the first region X1 as the second portion. The diameter of the first tapered shaft 13b21c gradually decreases from the shaft diameter N2 equivalent to the diameter of the large-diameter shaft 13b21b to the shaft diameter N1 equivalent to the diameter of the reference shaft 13b21a.

The large-diameter shaft 13b21b disposed at the other end of the second conveying screw 13b2 in the second direction of the second conveying screw 13b2 (in other words, at a position corresponding to the first communication port 13f) increases the height of the developer G in the vicinity of the first communication port 13f in the second conveyance path B2, and thus the developer G can be easily delivered (lifted) from the second conveyance path B2 to the first conveyance path B1 via the first communication port 13f. As a result, the above-described structure enables supplying a sufficient amount of developer G from the second conveyance path B2 to the first conveyance path B1 via the first communication port 13f. The above-described effect is sufficiently achieved because the one end of the large-diameter shaft 13b21b in the second direction of the second conveying screw 13b2 (in other words, the upstream end of the large-diameter shaft 13b21b in the developer conveyance direction) is positioned sufficiently away from the one end of the first communication port 13f in the second direction of the second conveying screw 13b2 toward upstream in the developer conveyance direction to increase the pressure of the developer in the vicinity of the first communication port 13f. In other words, the second predetermined distance is experimentally determined so that the second conveying screw generates a sufficiently large pressure of the developer G in the first communication port. In the experiments conducted by the present inventors, the first predetermined distance was preferably from 11 mm to 15 mm, and more preferably from 12 mm to 14 mm.

In addition, the first tapered shaft 13b21c between the large-diameter shaft 13b21b and the reference shaft 13b21a smoothly flows the developer G from the second region X2 toward the first region X1 in the second conveyance path B2, which reduces stress applied to the developer G to be smaller than stress applied to the developer G in a structure not including the first tapered shaft 13b21c.

The small-diameter shaft 13b11b disposed at one end of the first conveying screw 13b1 in the first direction of the first conveying screw 13b1 (in other words, at the position corresponding to the first communication port 13f) decreases the height of the developer G in the vicinity of the first communication port 13f in the first conveyance path B1 and thus reduces the pressure of the developer G delivered from the second conveyance path B2 to the first conveyance path B1 via the first communication port 13f. As a result, the above-described structure increases the fluidity (in other

words, the conveying performance) of the developer G in the first conveyance path B1 and uniforms the height of the developer G in the axial direction of the developing roller 13a, which enables stably and uniformly supplying the developer G to the developing roller 13a. The above-described effect is sufficiently achieved because the other end of the small-diameter shaft 13b11b in the first direction of the first conveying screw 13b1 (in other words, the downstream end of the small-diameter shaft 13b11b in the developer conveyance direction) is positioned sufficiently away from the other end of the first communication port 13f in the first direction of the first conveying screw 13b1 toward downstream in the developer conveyance direction to decrease the pressure of the developer in the vicinity of the first communication port 13f. In other words, the first predetermined distance is experimentally determined so that the first conveying screw generates a sufficiently small pressure of the developer G in the first communication port and the developer in the second conveying path smoothly flows into the first conveying path. In the experiments conducted by the present inventors, the first predetermined distance was preferably from 11 mm to 15 mm, and more preferably from 12 mm to 14 mm.

In addition, the tapered shaft 13b11c between the small-diameter shaft 13b11b and the reference shaft 13b11a smoothly flows the developer G from the first region Z1 toward the second region Z2 in the first conveyance path B1, which reduces stress applied to the developer G to be smaller than stress applied to the developer G in a structure not including the tapered shaft 13b11c.

As described above, the large-diameter shaft 13b21b on the second conveying screw 13b2 in the vicinity of the first communication port 13f and the small-diameter shaft 13b11b on the first conveying screw 13b1 in the vicinity of the first communication port 13f suitably adjusts the amount of the developer G delivered from the second conveyance path B2 to the first conveyance path B1 in the first communication port 13f not to be excessive or insufficient. As a result, the above-described structure prevents a disadvantage that an excessive amount of the developer G delivered to the first conveyance path B1 causes a white belt-like abnormal image occurred at one end of an outputted image in a width direction of the sheet orthogonal to the sheet conveyance direction and a disadvantage that an insufficient amount of the developer G delivered to the first conveyance path B1 causes an uneven image density (that is, an abnormal image) corresponding to the rotation pitch of the first conveying screw 13b1 in the outputted image.

The above-described effect is achieved to some extent even in a structure including the large-diameter shaft 13b21b on the second conveying screw 13b2 in the vicinity of the first communication port 13f but not including the small-diameter shaft 13b11b on the first conveying screw 13b1 in the vicinity of the first communication port 13f. In particular, the first tapered shaft 13b21c on the second conveying screw 13b2 is useful in this case.

Referring to FIG. 6, the second tapered shaft 13b21d in the second shaft 13b21 of the second conveying screw 13b2 according to the present embodiment is formed to extend from the large-diameter shaft 13b21b to the other end of the second conveying screw 13b2 in the second direction of the second conveying screw 13b2 (in other words, to the right side of the developing device 13 in FIG. 6). The shaft diameter of the second tapered shaft 13b21d gradually decreases from the shaft diameter N1 equivalent to the shaft

diameter of the large-diameter shaft $13b21b$ toward the other end of the second conveying screw $13b2$ in the second direction.

Since the second tapered shaft $13b21d$ disposed as described above reduces the conveying performance of the developer G around the second tapered shaft $13b21d$, the second tapered shaft $13b21d$ prevents the developer G from staying at the other end of the second conveyance path B2 in the second direction of the second conveying screw $13b2$, increasing the developer pressure, agglomerating, or leaking out from the other end of the developing device 13 in the second direction.

In the developing device 13 according to the present embodiment, the rotational speed of the second conveying screw $13b2$ is set to be about 1.16 times as high as the rotational speed of the first conveying screw $13b1$.

This increases the efficiency of delivering the developer G from the second conveyance path B2 to the first conveyance path B1 through the first communication port 13f.

In addition, the second conveying screw $13b2$ in the present embodiment is designed such that the screw diameters of the second screw portion $13b22$ are uniform in the first region X1 (in other words, the second portion) of the second conveying screw $13b2$ in the second conveyance path B2. In other words, the second screw portion has the same screw diameter over the second portion of the second conveying screw.

Specifically, the height of the screw of the second screw portion $13b22$ is designed to be 2.75 mm in the first region X1 (in other words, the second portion) of the second conveying screw $13b2$.

This enables the developer G to be delivered from the second conveyance path B2 to the first conveyance path B1 in a well-balanced manner in the first communication port 13f.

The present inventors performed experiments using the developing device 13 according to the present embodiment. In the experiments, the shaft diameter N1 of the large-diameter shaft $13b21b$ of the second conveying screw $13b2$ and the shaft diameter M1 of the small-diameter shaft $13b11b$ of the first conveying screw $13b1$ were changed, and whether the abnormal image occurred was examined. FIG. 7 is a graph illustrating the results of the experiments.

In FIG. 7, the horizontal axis represents the shaft diameter N1 of the large-diameter shaft $13b21b$ of the second conveying screw $13b2$ that are three levels of 5, 6, and 7 mm, and the vertical axis represents the height of the developer G in the first conveyance path B1. In FIG. 7, the bar chart with light hatching indicates the height of the developer G in the first conveyance path B1 in which the shaft diameter M1 of the small-diameter shaft $13b11b$ of the first conveying screw $13b1$ is 8 mm, and the bar chart with dark hatching indicates the height of the developer G in the first conveyance path B1 in which the shaft diameter M1 of the small-diameter shaft $13b11b$ of the first conveying screw $13b1$ is 6.5 mm.

In FIG. 7, the “abnormal image due to the large height of the developer” is the white band image, and the “abnormal image due to the small height of the developer” is an uneven density image. An abnormal image occurrence region of each abnormal image is the range from a dashed line toward the white arrow direction.

From the results of the experiments illustrated in FIG. 7, it was found that designing the shaft diameter N1 of the large-diameter shaft $13b21b$ of the second conveying screw $13b2$ to be 7 mm and designing the shaft diameter M1 of the small-diameter shaft $13b11b$ of the first conveying screw

$13b1$ to be 6.5 mm resulted in the height of the developer G in the first conveyance path B1 within a range of 10 to 14 mm, in which the white band image and the uneven density image did not occur.

As described above, the developing device according to the present embodiment contains the developer G inside the developing device and includes the developing roller $13a$ as the developer bearer that develops the latent image formed on the surface of the photoconductor drum 11 as the image bearer. The developing device includes the first conveying screw $13b1$ disposed in the first conveyance path B1 to face the developing roller $13a$, and the first conveying screw $13b1$ conveys the developer G from one end of the first conveying screw $13b1$ to the other end of the first conveying screw $13b1$ in the first direction along the axial direction of the first conveying screw $13b1$ to supply the developer G to the developing roller $13a$. The developing device includes the second conveying screw $13b2$ disposed in the second conveyance path B2 facing the first conveying screw $13b1$ via the partition $13e$, and the second conveying screw $13b2$ conveys the developer G from the one end of the second conveying screw $13b2$ to the other end of the second conveying screw $13b2$ in the second direction opposite to the first direction. The second direction is along the axial direction of the second conveying screw $13b2$.

In addition, the developing device has the first communication port $13f$ opened in the partition $13e$ so as to communicate the one end of the first conveyance path B1 in the first direction and the other end of the second conveyance path B2 in the second direction and the second communication port $13g$ opened in the partition $13e$ so as to communicate the other end of the first conveyance path B1 in the first direction and the one end of the second conveyance path B2 in the second direction.

The first conveying screw $13b1$ has the first region Z1 and the second region Z2. The first region Z1 extends from one end of the first conveying screw $13b1$ in the first direction along the axial direction of the first conveying screw $13b1$ to the position away from the first communication port $13f$ toward the center of the first conveying screw $13b1$ in the axial direction by the first predetermined distance H1. The first region Z1 is referred to as the first portion of the first conveying screw $13b1$. The second region Z2 is the region of the first conveying screw $13b1$ other than the first region Z1. The second region Z2 is referred to as the first adjacent portion adjacent to the first portion.

The first shaft $13b11$ has the shaft diameter M1 in the second region Z2 as the first adjacent portion adjacent to the first portion and the shaft diameter M2 in the first region Z1 as the first portion smaller than the shaft diameter M1, and the first screw portion $13b12$ is wound around the first shaft $13b11$. The second conveying screw $13b2$ has the first region X1 and the second region X2. The first region X1 extends from the other end of the second conveying screw $13b2$ in the second direction along the axial direction of the second conveying screw $13b2$ to the position away from the first communication port $13f$ toward the center of the second conveying screw $13b2$ in the axial direction by the second predetermined distance H2. The first region X1 is referred to as the second portion of the second conveying screw $13b2$. The second shaft $13b21$ has the shaft diameter N1 in the second region X2 as the second adjacent portion adjacent to the second portion and the shaft diameter N2 in the first region X1 as the second portion larger than the shaft diameter N1, and the second screw portion $13b22$ is wound around the second shaft $13b21$.

21

The above-described structure can suitably optimize the amount of developer G delivered from the second conveyance path B2 to the first conveyance path B1 through the first communication port 13f.

In the present embodiment, the present disclosure is applied to the image forming apparatus including the developing device 13 configured as a unit that is detachable from the body of the image forming apparatus as a single unit. However, the present disclosure is not limited to this and may be applied to an image forming apparatus including a process cartridge configured by a part or all of the image forming device. In this case, the workability of maintenance of the image forming device is enhanced.

Note that the term "process cartridge" used in the present disclosure means a detachable unit including an image bearer and at least one of a charging device to charge the image bearer, a developing device to develop a latent image on the image bearer, and a cleaning device to clean the image bearer that are united together and is removably attached as a single unit in the apparatus body of the image forming apparatus.

In the present embodiment, the present disclosure is applied to the developing device 13 including the first conveyance path B1 disposed above the second conveyance path B2, and the second conveyance path B2 is disposed so as to face the developing roller 13a via the first conveyance path B1. However, the developing device to which the present disclosure is applied is not limited to this, and the present disclosure may be applied to a developing device including, for example, the first conveyance path and the second conveyance path that are horizontally arranged, and the second conveyance path is disposed so as to face the developing roller via the first conveyance path.

In the present embodiment according to the present disclosure, the developing device 13 includes the two-component developer including toner and carrier. Alternatively, the developing device to which the present disclosure is applied may include a one-component developer (i.e., toner, which may include additives). In this case, the developing roller in the developing device may be disposed in contact with the photoconductor drum as the image bearer.

In the present embodiment, the first conveying screw 13b1 includes the first screw portion 13b12 having three threads, and the second conveying screw 13b2 includes the second screw portion 13b22 having two threads, but the number of threads in the screw portion of the first and second conveying screws 13b1 and 13b2 is not limited to the above-described combination.

In the present embodiment, the second conveying screw 13b2 includes the cutout portion W and the projection 13b23 in the second region X2 but may not include the cutout portion W and the projection 13b23.

Such cases also provide substantially the same effects as the effects described above.

Note that embodiments of the present disclosure are not limited to the above-described embodiments, and it is apparent that the above-described embodiments can be appropriately modified within the scope of the technical idea of the present disclosure in addition to what is suggested in the above-described embodiments. The number, position, and shape of the components described above are not limited to those embodiments described above. Desirable number, position, and shape can be determined to perform the present disclosure.

Note that aspects of the present disclosure may be applicable to, for example, combinations of first to twelfth aspects as follows.

22

First Aspect

In a first aspect, a developing device includes a developer bearer, a first conveying screw, a partition, and a second conveying screw. The first conveying screw is disposed in a first conveyance path and faces the developer bearer. The first conveying screw conveys developer from one end of the first conveyance path to another end of the first conveyance path in a first direction along an axial direction of the first conveying screw. The second conveying screw is disposed in a second conveyance path and faces the first conveying screw via the partition. The second conveying screw conveys the developer from one end of the second conveyance path to another end of the second conveyance path in a second direction opposite to the first direction along an axial direction of the second conveying screw. The partition has a first communication port communicating the one end of the first conveyance path and the another end of the second conveyance path and a second communication port communicating the another end of the first conveyance path and the one end of the second conveyance path. The first conveying screw includes a first shaft, a first screw portion wound around the first shaft, a first portion, and a first adjacent portion adjacent to the first portion. The first portion has a first shaft and ranges from one end of the first conveying screw, corresponding to the one end of the first conveyance path, to a position away from the first communication port toward a center of the first conveying screw by a first predetermined distance in the axial direction of the first conveying screw. The first adjacent portion has a second shaft diameter larger than the first shaft diameter. The second conveying screw includes a second shaft, a second screw portion wound around the second shaft, a second portion, and a second adjacent portion adjacent to the second portion. The second portion has a third shaft diameter and ranges from another end of the second conveying screw, corresponding to the another end of the second conveyance path, to a position away from the first communication port toward a center of the second conveying screw by a second predetermined distance in the axial direction of the second conveying screw. The second adjacent portion has a fourth shaft diameter smaller than the third shaft diameter.

Second Aspect

In a second aspect, the second shaft of the second conveying screw in the developing device according to the first aspect includes the second portion having a large-diameter shaft and the second adjacent portion having a reference shaft and a first tapered shaft. The large-diameter shaft has the third shaft diameter. The reference shaft has the fourth shaft diameter smaller than the third shaft diameter. The first tapered shaft is between the large-diameter shaft and the reference shaft. The first tapered shaft has a shaft diameter that gradually decreases from the third shaft diameter to the fourth shaft diameter.

Third Aspect

In a third aspect, the second shaft in the developing device according to the second aspect further includes a second tapered shaft adjacent to the large-diameter shaft. The second tapered shaft extends to the another end of the second conveying screw in the axial direction of the second conveying screw and has a shaft diameter gradually decreasing from the third shaft diameter to the fourth shaft diameter.

23

Fourth Aspect

In a fourth aspect, the first shaft of the first conveying screw in the developing device according to any one of the first to third aspects includes the first portion having a small-diameter shaft and the first adjacent portion having a reference shaft and a tapered shaft. The small-diameter shaft has the first shaft diameter. The reference shaft has the second shaft diameter larger than the first shaft diameter. The tapered shaft is between the small-diameter shaft and the reference shaft. The tapered shaft has a shaft diameter that gradually increases from the first shaft diameter to the second shaft diameter.

Fifth Aspect

In a fifth aspect, the developing device according to any one of the first to fourth aspects has the first predetermined distance equal to the second predetermined distance.

Sixth Aspect

In a sixth aspect, a developing device includes a developer bearer, a first conveying screw, a partition, and a second conveying screw. The first conveying screw is disposed in a first conveyance path and faces the developer bearer. The first conveying screw conveys developer from one end of the first conveyance path to another end of the first conveyance path in a first direction along an axial direction of the first conveying screw. The second conveying screw is disposed in a second conveyance path and faces the first conveying screw via the partition. The second conveying screw conveys the developer from one end of the second conveyance path to another end of the second conveyance path in a second direction opposite to the first direction along an axial direction of the second conveying screw. The partition has a first communication port communicating the one end of the first conveyance path and the another end of the second conveyance path and a second communication port communicating the another end of the first conveyance path and the one end of the second conveyance path. The second conveying screw includes a second shaft, a second screw portion wound around the second shaft, a second portion, and a second adjacent portion adjacent to the second portion. The second portion has a large-diameter shaft having a third shaft diameter and ranges from another end of the second conveying screw in the axial direction of the second conveying screw, corresponding to the another end of the second conveyance path, to a position away from the first communication port toward a center of the second conveying screw by a second predetermined distance in the axial direction of the second conveying screw. The second adjacent portion has a reference shaft and a first tapered shaft. The reference shaft has a fourth shaft diameter smaller than the third shaft diameter. The first tapered shaft is between the large-diameter shaft and the reference shaft. The first tapered shaft has a shaft diameter that gradually decreases from the third shaft diameter to the fourth shaft diameter.

Seventh Aspect

In a seventh aspect, the second shaft in the developing device according to the sixth aspect further includes a second tapered shaft adjacent to the large-diameter shaft. The second tapered shaft extends to the another end of the second conveying screw in the axial direction of the second

24

conveying screw and has a shaft diameter gradually decreasing from the third shaft diameter to the fourth shaft diameter.

Eighth Aspect

In an eighth aspect, a rotational speed of the second conveying screw is faster than a rotational speed of the first conveying screw in the developing device according to any one of the first to seventh aspects.

Ninth Aspect

In a ninth aspect, the second screw portion in the developing device according to any one of the first to eighth aspects has a same screw diameter over the second portion.

Tenth Aspect

In a tenth aspect, the second conveyance path is below the first conveyance path in the developing device according to any one of the first to ninth aspects.

Eleventh Aspect

In an eleventh aspect, the first predetermined distance in the developing device according to any one of the first to tenth aspects is from 11 mm to 15 mm.

Twelfth Aspect

In a twelfth aspect, the first predetermined distance in the developing device according to any one of the first to eleventh aspects is from 12 mm to 14 mm.

Thirteenth Aspect

In a thirteenth aspect, the second predetermined distance in the developing device according to any one of the first to twelfth aspects is from 11 mm to 15 mm.

Fourteenth Aspect

In a fourteenth aspect, the second predetermined distance in the developing device according to any one of the first to thirteenth aspects is from 12 mm to 14 mm.

Fifteenth Aspect

In a fifteenth aspect, a process cartridge removably installed to a body of an image forming apparatus includes the developing device according to any one of the first to fourteenth aspects and an image bearer.

Sixteenth Aspect

In a sixteenth aspect, an image forming apparatus includes the developing device according to any one of the first to fifteenth aspects.

The above-described embodiments are illustrative and do not limit the present invention. Thus, numerous additional modifications and variations are possible in light of the above teachings. For example, elements and/or features of different illustrative embodiments may be combined with each other and/or substituted for each other within the scope of the present invention.

25

The invention claimed is:

1. A developing device comprising:
    - a developer bearer;
    - a first conveying screw disposed in a first conveyance path and facing the developer bearer, the first conveying screw to convey developer from one end of the first conveyance path to another end of the first conveyance path in a first direction along an axial direction of the first conveying screw;
    - a partition; and
    - a second conveying screw disposed in a second conveyance path and facing the first conveying screw via the partition, the second conveying screw to convey the developer from one end of the second conveyance path to another end of the second conveyance path in a second direction opposite to the first direction along an axial direction of the second conveying screw,
- wherein the partition has:
- a first communication port communicating the one end of the first conveyance path and the another end of the second conveyance path; and
  - a second communication port communicating the another end of the first conveyance path and the one end of the second conveyance path,
- the first conveying screw includes:
- a first shaft;
  - a first screw portion wound around the first shaft;
  - a first portion having a first shaft diameter, the first portion ranged from one end of the first conveying screw, corresponding to the one end of the first conveyance path, to a position away from the first communication port toward a center of the first conveying screw by a first predetermined distance in the axial direction of the first conveying screw; and
  - a first adjacent portion adjacent to the first portion, the first adjacent portion having a second shaft diameter larger than the first shaft diameter; and
- the second conveying screw includes:
- a second shaft;
  - a second screw portion wound around the second shaft;
  - a second portion having a third shaft diameter, the second portion ranged from another end of the second conveying screw, corresponding to the another end of the second conveyance path, to a position away from the first communication port toward a center of the second conveying screw by a second predetermined distance in the axial direction of the second conveying screw; and
  - a second adjacent portion adjacent to the second portion, the second adjacent portion having a fourth shaft diameter smaller than the third shaft diameter.
2. The developing device according to claim 1, wherein the second shaft of the second conveying screw includes:
    - the second portion having a large-diameter shaft having the third shaft diameter; and
    - the second adjacent portion includes:
      - a reference shaft having the fourth shaft diameter smaller than the third shaft diameter; and
      - a first tapered shaft between the large-diameter shaft and the reference shaft, the first tapered shaft having a shaft diameter that gradually decreases from the third shaft diameter to the fourth shaft diameter.
  3. The developing device according to claim 2, wherein the second shaft further includes a second tapered shaft adjacent to the large-diameter shaft, and the second tapered shaft extends to the another end of the second conveying screw in the axial direction of the

26

second conveying screw and has a shaft diameter gradually decreasing from the third shaft diameter to the fourth shaft diameter.

4. The developing device according to claim 1, wherein the first shaft of the first conveying screw includes:
  - the first portion having a small-diameter shaft having the first shaft diameter;
  - the first adjacent portion including a reference shaft having the second shaft diameter larger than the first shaft diameter, and
  - a tapered shaft between the small-diameter shaft and the reference shaft, the tapered shaft having a shaft diameter that gradually increases from the first shaft diameter to the second shaft diameter.
5. The developing device according to claim 1, wherein: the first predetermined distance is equal to the second predetermined distance.
6. The developing device according to claim 1, wherein: a rotational speed of the second conveying screw is faster than a rotational speed of the first conveying screw.
7. The developing device according to claim 1, wherein; the second screw portion has a same screw diameter over the second portion.
8. The developing device according to claim 1, wherein; the second conveyance path is below the first conveyance path.
9. The developing device according to claim 1, wherein; the first predetermined distance is from 11 mm to 15 mm.
10. The developing device according to claim 1, wherein; the first predetermined distance is from 12 mm to 14 mm.
11. The developing device according to claim 1, wherein: the second predetermined distance is from 11 mm to 15 mm.
12. The developing device according to claim 1, wherein: the second predetermined distance is from 12 mm to 14 mm.
13. A process cartridge removably installed to a body of an image forming apparatus, comprising:
  - the developing device according to claim 1; and
  - an image bearer onto which latent images are formed by the developing device.
14. An image forming apparatus comprising the developing device according to claim 1.
15. The developing device according to claim 1, wherein: a rotational speed of the second conveying screw is faster than a rotational speed of the first conveying screw.
16. The developing device according to claim 1, wherein: the second screw portion has a same screw diameter over the second portion of the second conveying screw.
17. A developing device comprising:
  - a developer bearer;
  - a first conveying screw disposed in a first conveyance path and facing the developer bearer, the first conveying screw to convey developer from one end of the first conveyance path to another end of the first conveyance path in a first direction along an axial direction of the first conveying screw;
  - a partition; and
  - a second conveying screw disposed in a second conveyance path and facing the first conveying screw via the partition, the second conveying screw to convey the developer from one end of the second conveyance path to another end of the second conveyance path in a second direction opposite to the first direction along an axial direction of the second conveying screw,

27

wherein the partition has:

- a first communication port communicating the one end of the first conveyance path and the another end of the second conveyance path; and
- a second communication port communicating the another end of the first conveyance path and the one end of the second conveyance path, and
- the second conveying screw includes:
- a shaft;
- a screw portion wound around the shaft;
- a portion including a large-diameter shaft having a large shaft diameter, the portion ranged from another end of the second conveying screw in the axial direction of the second conveying screw, corresponding to the another end of the second conveyance path, to a position away from the first communication port toward a center of the second conveying screw by a predetermined distance in the axial direction of the second conveying screw; and
- an adjacent portion adjacent to the portion, the adjacent portion including:
- a reference shaft having a diameter smaller than the large shaft diameter; and
- a first tapered shaft between the large-diameter shaft and the reference shaft, the first tapered shaft having a shaft

5 10 15 20

28

diameter that gradually decreases from the large shaft diameter to the diameter of the reference shaft.

18. The developing device according to claim 17, wherein:

- the shaft further includes a second tapered shaft adjacent to the large-diameter shaft, and
- the second tapered shaft extends to the another end of the second conveying screw in the axial direction of the second conveying screw and has a shaft diameter gradually decreasing from the large shaft diameter to the diameter of the reference shaft.

19. The developing device according to claim 17, wherein:

- the shaft further includes a second tapered shaft adjacent to the large-diameter shaft, and the second tapered shaft extends to the another end of the second conveying screw in the axial direction of the second conveying screw and has a shaft diameter gradually decreasing from the large shaft diameter.

20. The developing device according to claim 17, wherein:

- the second conveyance path is below the first conveyance path.
